(57) **CLAIM**

The ornamental design for a customer point of sale terminal, as shown and described.

DESCRIPTION

FIG. 1 is a perspective view of the front, left, and top of a customer point of sale terminal according to the new design. FIG. 2 is a front view of the user terminal.

FIG. 3 is a rear view of the user terminal.

FIG. 4 is a right side view of the user terminal.

FIG. 5 is a left side view of the user terminal.

FIG. 6 is a top side view of the user terminal.

FIG. 7 is a bottom side view of the user terminal; and,

FIG. 8 is a perspective view of the front, right, and bottom of a user terminal according to the new design.

The article in which the design is embodied is a user terminal for conducting point-of-sale (POS) transactions in a retail environment.

1 Claim, 8 Drawing Sheets
